UNITED STATES PATENT OFFICE.

GEORGE A. WEBER, OF STAMFORD, CONNECTICUT, ASSIGNOR TO THE WEBER RAILWAY JOINT MANUFACTURING COMPANY, OF NEW YORK, N. Y., A CORPORATION OF WEST VIRGINIA.

RAILWAY-RAIL JOINT.

SPECIFICATION forming part of Letters Patent No. 739,464, dated September 22, 1903.

Application filed June 2, 1902. Serial No. 109,938. (No model.)

To all whom it may concern:

Be it known that I, GEORGE A. WEBER, a citizen of the United States, residing in Stamford, county of Fairfield, and State of Connecticut, have invented certain new and useful Improvements in Railway-Rail Joints, of which the following is a specification.

My present improvement relates to railway-rail joints in which a bond is employed to conduct the current of electricity from one rail-section to the next; and its objects are to improve upon the construction of such joints.

Further objects will hereinafter appear; and to these ends the invention consists of a joint for carrying out the above object, constructed substantially as hereinafter described and claimed in this specification and shown in the accompanying drawings.

20 In the accompanying drawings, Figure 1 is a perspective view of a railway-rail joint embodying my improvement. Fig. 2 is a transverse section of the same, taken at the plane where the ends of two adjacent rail-sections meet. Fig. 3 is a perspective view of the shoe which is comprised in said joint.

A' A² designate the end portions of adjacent rail-sections of a railway-track. They may be of any suitable construction. They 30 are united by a joint comprising a shoe B, which has a base b' and an upright b². The rail-sections A' A² rest upon the base b' of the shoe, and the upright b² of the shoe extends opposite one side of the rail-sections. 35 Intermediate of the upright b² and the rail-sections is a fish-plate or bar C, which is shown as having outwardly-extended flanges, and intermediate of this fish-plate or bar and the upright of the shoe is a bar D of packing 40 material, such as wood. On the other side of the rail-sections is a fish-plate or bar E. Bolts F, extending through the fish-plates or bars C E, the bar of packing material D, and the upright b² of the shoe, secure all these 45 parts together. The shoe B and the plates or bars C E may be made of any suitable metal, such as iron or steel.

In the base b' of the shoe B is a pocket b³, which extends downwardly and is here shown 50 as formed integrally with the base of the shoe

by cutting an incision b⁴ for a certain distance in the base and bending a portion of the base downwardly. This pocket has a central deeply-depressed portion b⁵ and other portions b⁶, which are slightly depressed.

55

G designates a bond, which may be made of copper or other suitable metal. It is made in the form of a strip of such thickness that its end portions may lie in the slightly-depressed portions b⁶ of the pocket b³ in the base of the shoe B and below the feet of the rail-sections A' A². At its middle portion it is bent downwardly, so as to extend into the deeply-depressed portion b⁵ of the said pocket b³. It may be united by solder to the feet of 65 the rail-sections.

By my improvement the bond is protected from injury and against all ordinary efforts at removal by malicious persons.

What I claim as my invention, and desire 70 to secure by Letters Patent, is—

1. In a railway-rail joint, the combination of a rail-support provided with a pocket extending longitudinally thereof, said pocket being centrally deeply depressed and slightly 75 depressed at opposite ends of the deeply-depressed portion, and a bond constructed to conform to the contour of said pocket, with end portions lying in the slightly-depressed end portions of the pocket, for substantially 80 the purposes set forth.

2. In a railway-rail joint, the combination of a rail-support, a portion of which is bent downwardly to form a pocket extending longitudinally of the support, said pocket being 85 centrally deeply depressed and slightly depressed at opposite ends of the deeply-depressed portion, and a bond constructed to conform to the contour of said pocket, with end portions lying in the slightly-depressed 90 end portions of the pocket, for substantially the purposes set forth.

In testimony whereof I have signed my name to this specification in the presence of two subscribing witnesses.

GEORGE A. WEBER.
